(57) **CLAIM**

The ornamental design for a combined tray and table, as shown and described.

DESCRIPTION

FIG. 1 is a top perspective view of a combined tray and table showing my new design;

FIG. 2 is a top plan view thereof.

FIG. 3 is a bottom plan view thereof.

FIG. 4 is a front elevation view thereof.

FIG. 5 is a left side elevation view thereof.

FIG. 6 is a rear elevation view thereof.

FIG. 7 is a right side elevation view thereof.

FIG. 8 is a side elevation view thereof taken along line 8—8 in FIG. 2; and,

FIG. 9 is another top perspective view thereof showing the design in an exploded condition.
